Whole No. 1398

Charles Probst of Hudson City, N.Y.
Letters Patent No. 33. dated April 9 1861.

The schedule referred to in these Letters Patent and making part of the same.

To all whom it may concern:

Be it known that I, Charles Probst, of Hudson City, in the State of New Jersey, have invented or produced a new and original design for window glass, which consists in the peculiar arrangement of leaves and stems represented in the accompanying drawing, which forms part of this Specification.

What I claim as my invention or production, and desire to secure by Letters Patent, is the peculiar arrangement and configuration of leaves and stems herein described and represented in the accompanying drawing, the same forming a new and ornamental design for window glass.

The above specification of my said design signed & witness
ed this fifth day of November 1860.

Ex^d   Witnesses.
